(57) **CLAIM**

The ornamental design for a laminator, as shown and described.

DESCRIPTION

FIG. 1 is a perspective view taken from the top, front, and right side of a laminator showing our new design;

FIG. 2 is a perspective view taken from the top, rear, and right side of the laminator shown in FIG. 1;

FIG. 3 is a top plan view of the laminator shown in FIG. 1;

FIG. 4 is a bottom view of the laminator shown in FIG. 1;

FIG. 5 is a front elevational view of the laminator shown in FIG. 1;

FIG. 6 is a rear elevational view of the laminator shown in FIG. 1;

FIG. 7 is a left elevational side view of the laminator shown in FIG. 1;

FIG. 8 is a right elevational side view of the laminator shown in FIG. 1;

FIG. 9 is a perspective view taken from the top, front, and right side of another embodiment of a laminator showing our new design;

FIG. 10 is a perspective view taken from the top, rear, and right side of the laminator shown in FIG. 9;

FIG. 11 is a top plan view of the laminator shown in FIG. 9;

FIG. 12 is a bottom view of the laminator shown in FIG. 9;

FIG. 13 is a front elevational view of the laminator shown in FIG. 9;

FIG. 14 is a rear elevational view of the laminator shown in FIG. 9;

FIG. 15 is a left elevational side view of the laminator shown in FIG. 9;

FIG. 16 is a right elevational side view of the laminator shown in FIG. 9;

FIG. 17 is a perspective view taken from the top, front, and right side of another embodiment of a laminator showing our new design;

FIG. 18 is a perspective view taken from the top, rear, and right side of the laminator shown in FIG. 17;

FIG. 19 is a top plan view of the laminator shown in FIG. 17;

FIG. 20 is a bottom view of the laminator shown in FIG. 17;

FIG. 21 is a front elevational view of the laminator shown in FIG. 17;

FIG. 22 is a rear elevational view of the laminator shown in FIG. 17;

FIG. 23 is a left elevational side view of the laminator shown in FIG. 17;

FIG. 24 is a right elevational side view of the laminator shown in FIG. 17;

FIG. 25 is a perspective view taken from the top, front, and right side of another embodiment of a laminator showing our new design;

FIG. 26 is a perspective view taken from the top, rear, and right side of the laminator shown in FIG. 25;

FIG. 27 is a top plan view of the laminator shown in FIG. 25;

FIG. 28 is a bottom view of the laminator shown in FIG. 25;

FIG. 29 is a front elevational view of the laminator shown in FIG. 25;

FIG. 30 is a rear elevational view of the laminator shown in FIG. 25;

FIG. 31 is a left elevational view of the laminator shown in FIG. 25; and,

FIG. 32 is a right elevational side view of the laminator shown in FIG. 25.

The broken lines are for illustration purposes only and form no part of the claimed design.
